DESIGN FOR A SHOE

André Perugia, Paris, France

Application October 21, 1940, Serial No. 95,959

Term of patent 3½ years

To all whom it may concern:

Be it known that I, André Perugia, a citizen of Italy, residing at Paris, 2, rue de la Paix, France, have invented a new, original, and ornamental Design for a Shoe, of which the following is a specification, reference being had to the accompanying drawing, forming part thereof.

I claim:

The ornamental design for a shoe, as shown.

ANDRÉ PERUGIA.
